UNITED STATES PATENT OFFICE.

HEIN DE VRIES, OF HOOD, CALIFORNIA.

DESIGN FOR A LOVING-CUP.

46,249.

Specification for Design.

Patented Aug. 11, 1914.

Application filed March 23, 1914. Serial No. 826,827. Term of patent 7 years.

To all whom it may concern:

Be it known that I, HEIN DE VRIES, a subject of the Queen of the Netherlands, residing at Hood, in the county of Sacramento and State of California, have invented a new, original, and ornamental Design for Loving-Cups, of which the following is a specification, reference being had to the accompanying drawing, forming part thereof.

Figure 1 is a perspective view of a loving

cup illustrating my improved design; and Fig. 2 is a similar view of the other side of the cup.

I claim:

The ornamental design for a loving cup, as shown.

HEIN DE VRIES.
